Primary Examiner — Kevin K Rudzinski*Assistant Examiner* — Evans David Delesline(57) **CLAIM**

I claim the ornamental design for a liquid-containing watch band, as shown and described.

DESCRIPTION

FIG. 1 is an elevated perspective view of the liquid-containing watch band of my claimed design;

FIG. 2 is a top view of the watch band of FIG. 1;

FIG. 3 is a bottom view of the watch band of FIG. 1;

FIG. 4 is a left side view of the watch band of FIG. 1;

FIG. 5 is a right side view of the watch band of FIG. 1;

FIG. 6 is a first end view of the watch band of FIG. 1; and,

FIG. 7 is a second end view of the watch band of FIG. 1. The broken lines showing a watch in FIG. 1 illustrate environmental structure and do not form a part of the claimed design.
